UNITED STATES PATENT OFFICE.

JOHN A. OLBON, OF HALEDON, NEW JERSEY, ASSIGNOR OF ONE-HALF TO FELIX SIMON, OF PATERSON, NEW JERSEY.

SPINNER FOR GAME DEVICES.

Application filed April 25, 1928. Serial No. 272,805.

This invention relates to spinners for game devices.

An important object of the invention is to provide a simple and inexpensive spinner 5 which is adapted to be self supporting in a vertical position, and which is provided with novel actuating means.

A further object is to provide novel supporting means for the wheel and the spinning means therefor.

A further object is to provide a novel form of wheel including stamped out teeth adapted to be engaged by suitable actuating means for spinning the wheel.

15 A further object is to provide means associated with the wheel and operative during rotation thereof for making clicking sounds and adapted to act, if desired, as a brake to prevent prolonged rotation of the 20 wheel at each operation thereof.

Other objects and advantages of the invention will become apparent during the course of the following description.

In the drawings I have shown one embodiment of the invention. In this showing,

25 Figure 1 is a front elevation,

Figure 2 is a side elevation,

Figure 3 is a perspective view of the support and associated elements, and,

30 Figure 4 is a section taken substantially on line 4—4 of Figure 3, parts being shown in elevation.

Referring to the drawings the numeral 10 designates a base preferably formed of sheet 35 metal. The base may be made circular, as shown, and is provided with a pair of spaced parallel stamped out flanges 11 forming guide-ways to receive a horizontal projection 12 formed at the lower end of a stand- 40 ard or support 13.

The standard 13 also is preferably formed of sheet metal and is provided along one vertical edge intermediate the ends thereof with a rearwardly bent flange 14, as clearly 45 shown in Figure 3. An actuating member 15 is pivotally connected to the flange 14 as at 16. The actuating member preferably is formed of sheet metal and lies flat against the flange 14, the forward or engaging portion 50 of the actuating member being twisted as at 17, for a purpose to be described.

An operating lever 18, also preferably 55 formed of sheet metal, lies flat against the flange 14 and is pivotally connected thereto as at 19. The forward end of the lever is

twisted as at 20 to form a finger piece whereby the device may be operated in a manner to be described. A link 21 is pivotally connected at opposite ends as at 22 to the actuating member 15 and lever 18 respectively.

A sleeve 23 is soldered or otherwise secured to a spinner 24. A shaft 25 is carried by the support 13 and may be provided at its outer end with a head 26 contacting with the outer face of the spinner 24. Any suitable means may be employed for securing the shaft to the support, and in the present instance the connection is shown as being accomplished by soldering as at 27. The 70 spinner 24 is provided with a plurality of equidistantly spaced circumferentially arranged teeth 28 which are preferably formed by stamping the metal of the spinner. These teeth project rearwardly of the 75 spinner and are adapted to be engaged by the end 17 of the actuating member 15.

The outer face of the spinner is divided by radial lines 29 to form spaces in which are printed or otherwise applied indicia 30, 80 shown in the present instance as being numerals running from 1 to 20. It will be apparent that any suitable number of divisions may be employed, and that any desired indicia may be applied thereto. A pointer 85 31 is secured as at 32 to the upper end of the support 13 and is associated with the dial of the spinner.

A toothed wheel 33 may be secured to the inner end of the sleeve 23 in a plane beyond the inner extremities of the teeth 28. A flexible element 34 is secured at its upper end to the support 13 as at 35 and has its lower end engaging the teeth of the wheel 33.

The operation of the device is as follows:

With the parts in the position shown in Figures 1, 2 and 3, the engaging end 17 of the actuating member 15 is arranged out of the path of travel of the teeth 28. To operate the device, it is merely necessary to 90 place the finger upon the outer end of the lever 18 and to depress it with a rapid downward movement. This action moves the rear end of the lever 18 upwardly together with the link 21, thus swinging the rear end of the actuating member 15 upwardly. Thus the engaging end 17 will be brought into engagement with the adjacent tooth 28, and the movement will be transmitted to the spinner to cause rotation thereof. The lever 105 110

18 is depressed to the dotted line position shown in Figure 2, under which conditions, the engaging end 17 of the actuating member 15 again will be arranged out of the path of travel of the teeth, thus permitting the spinner to rotate until it comes to rest. The winning number is then read in connection with the pointer 31, and the game in connection with which the device is employed is played accordingly.

The flexible element 34 may be in the form of a light flexible leaf spring, and is intended to escape over the teeth of the wheel 33 to cause a rapid clicking sound while the spinner is rotating. The flexible element may possess a sufficient degree of resilience to provide a slight braking action to prevent the spinner from rotating too freely.

It is to be understood that the form of the invention herewith shown and described is to be taken as a preferred example of the same and that various changes in the shape, size and arrangement of parts may be resorted to without departing from the spirit 25 of the invention or the scope of the subjoined claims.

I claim:

1. A device of the character described comprising a vertical support, a spinner rotatably mounted on said support adjacent its upper end, an actuating member pivotally connected intermediate its ends to said support, a lever pivotally connected intermediate its ends to said support and arranged substantially parallel to said actuating member, a link pivotally connected at one end to one end of said actuating member and at its opposite end to one end of said lever, the other end of said actuating member being adapted to engage said spinner, the other end of said lever being provided with a finger piece projecting from said support.

2. A device of the character described comprising a vertical support, a spinner rotatably mounted on said support adjacent its upper end and provided on its rear face

with a plurality of circularly arranged projections, an actuating member pivotally connected intermediate its ends to said support and having one end adapted to engage said projections, said actuating member being movable to either of two positions with said end thereof out of the path of travel of said projections, a lever pivotally connected intermediate its ends to said support and having one end projecting therefrom and constituting a finger piece, and a link connecting the other end of said lever to the other end of said actuating member.

3. A device constructed in accordance with claim 2 wherein the body of said support is arranged substantially parallel to said spinner and is provided with a vertically extending flange arranged substantially at right angles to said spinner, said actuating member and said lever being pivotally connected to said flange.

4. A device of the character described comprising a sheet metal base having a pair of spaced parallel horizontal guides stamped upwardly therefrom, a vertical sheet metal support arranged above said base and having its lower end bent substantially horizontally and slidably mounted in said guides, a spinner rotatably supported on said support adjacent the upper end of and substantially parallel to the body of said support, a vertical flange carried by said support substantially at right angles to the body thereof, a pair of members pivotally connected intermediate their ends to said flange, a link pivotally connected at opposite ends to one end of each of said members, the other end of one of said members extending from said support and constituting a finger piece, and a plurality of circularly arranged projections carried by said spinner and adapted to be engaged by the other end of the other of said members.

In testimony whereof I affix my signature.

JOHN A. OLBON.
